Irving J. Nudelman, Chicago, Ill.

Application January 31, 1944, Serial No. 112,386

Term of patent 14 years

(Cl. D44—29)

To all whom it may concern:

Be it known that I, Irving J. Nudelman, a citizen of the United States, residing at Chicago, in the county of Cook and State of Illinois, whose post-office address is 4609 N. Monticello Avenue, Chicago, Illinois, have invented a new, original, and ornamental Design for a Cup Holder, of which the following is a specification, reference being had to the accompanying drawing, forming a part thereof.

In the drawing:

Fig. 1 is a plan view of a cup holder showing my design; and

Fig. 2 is a side elevational view thereof.

I claim:

The ornamental design for a cup holder, as shown.

IRVING J. NUDELMAN.
